Des. 240,381
Patented July 6, 1976

240,381

COMBINER DRAWER FRONT AND PULL THEREFOR

Michiharu Tazaki, Yokohama, Japan, assignor to
Kyoei Kogyo Kabushiki Kaisha

Filed Mar. 3, 1975, Ser. No. 555,058

Term of patent 14 years

Int. Cl. D6—06

U.S. Cl. D6—192

FIG-1

FIG-2

FIG-3

FIG-5

FIG-6

FIG-4

FIG. 1 is a perspective view of a combined drawer front and pull therefor according to my invention;

FIG. 2 is a front elevation thereof;

FIG. 3 is a right hand end elevation thereof;

FIG. 4 is a left hand elevation thereof;

FIG. 5 is a top plan view thereof; and

FIG. 6 is a bottom plan view thereof.

I claim:

The ornamental design for a combined drawer front and pull therefor, substantially as shown.
